FILM FEEDING APPARATUS

Oscar J. Holmes, Chicago, Ill.

Application January 29, 1940, Serial No. 316,086

17 Claims. (Cl. 271—2.3)

This invention relates to sound-on-film reproducing or recording apparatus and more particularly to a control mechanism for maintaining a film at constant velocity for sound translation.

The apparatus for recording and reproducing systems now commonly includes means such as a flywheel by which it is sought to smooth out the irregularities of motion of the film past the recording or reproducing point. The undamped flywheel of relatively large mass as at first employed possessed a number of disadvantages, chief among which were that it formed an oscillating system with the film-directing idle rollers or driving sprockets, which system had a period of its own and, instead of absorbing all irregularities in the film motion, aggravated many such irregularities. It was subsequently proposed to dampen the flywheel in various ways, employing a viscous incompressible fluid such as oil which exerted a drag upon the flywheel which it was thought would tend to resist a change in velocity of the flywheel. However, such constructions have not been entirely satisfactory for a number of reasons, of which the following appear to applicant to be the most important.

The viscosity of the incompressible fluid or oil varies with temperature to a great degree. When the machine is cold, the oil is of such relatively high viscosity that it imposes a great drag upon the flywheel, places a great strain upon the film and film-driving wheels, and is, generally speaking, quite unsatisfactory for the performance of its intended function. As the machine warms up or becomes hot, the viscosity of the oil changes considerably so that its drag upon the flywheel varies during the heating-up period and, instead of ironing out irregularities in the film motion, it causes and accentuates such irregularities. When the oil used has the best or most advantageous viscosity for operation after the machine has reached the normal operating temperature, its viscosity, when the machine first starts up and during the initial portion of the heating-up period, is so great that it may be said to be entirely unsatisfactory. Sacrifice, therefore, has to be made in regard to the viscosity of the oil for best operating conditions when the oil has become fully heated in order that some satisfaction of operation may be obtained when starting the machine and during the heating-up period.

Furthermore, in such oil-dampened flywheel systems and because of the incompressible character of the fluid or oil, the length of the film loops between the drum or sprocket on the fly-

wheel shaft and the rollers or sprockets over which the film passes to and from the drum or sprocket on the flywheel shaft becomes greater or less as irregularities in the motion of the film cause the film to speed up or slow down and as spliced joints in the film pass over the drum or sprocket on the flywheel shaft. Also, it has been observed that the particles at the edges of the sprocket openings on one side of the film, that project outwardly the minutest amount from the face of the film, cause, as the film passes over the drum or sprocket on the flywheel shaft, this oscillating increase and decrease in the size of these film loops. As the film loop in advance of the flywheel driving and driven drum or sprocket tends to increase in size due to an increase in the longitudinal speed of the film, the film itself stores up a certain amount of energy which tends to cause the film to slide or slip relatively to the drum or sprocket and to increase without changing the speed of the drum the length of the loop on the other side of the drum, which causes distortion of the sound, and, if this slippage is resisted, sets up a transverse vibration or ripple motion which is transmitted by the film from the loop to the film on the drum or sprocket. When the film loop between the flywheel driving and driven drum and the following idle roller or sprocket tends to increase due to a change in the longitudinal velocity of the film, the body of the film in this loop tends to cause the film to slip rearwardly relative to the flywheel driving and driven drum or sprocket without changing the speed thereof and to increase the length of the loop in advance of such drum or sprocket which, of course, produces distortion and, if this slippage is resisted, sets up a transverse vibration or ripple motion which, as before stated, is reflected upon the portion of the film on the flywheel driving and driven drum or sprocket.

This flapping of the film over the idle rollers or sprockets on opposite sides of the drum or sprocket on the flywheel shaft is thus reflected in a flapping of the film on the flywheel driving and driven drum or sprocket and, since the sound is reproduced from the film as it passes over such drum or sprocket, this flapping of the film and/or the slippage of the film relative to the flywheel driving and driven drum or sprocket causes distortion of the sound and creates a masking oscillation of audible frequency and objectionable intensity such as to seriously impair the fidelity of the sound reproduced. In the case of the recorder, this flapping of the film and/or the

slippage of the film relative to the flywheel driving and driven drum or sprocket introduces distortions into the sound recorded which, of course, are further accentuated when the film is 5 produced by means of a machine employing a similarly oil damped flywheel. Thus, while oil-damped flywheels may be said to be more or less effective to prevent irregularities in longitudinal velocity of the film when the oil has been 10 come fully heated, they cause a transverse vibration or flapping of the film and/or a longitudinally reflected ripple motion or wave, which produces distortions which are worse in many cases than those sought to be avoided by the substitution of such a flywheel for a previously employed undamped flywheel.

It is, therefore, an object of applicant's invention to provide means tending sufficiently to resist change in longitudinal velocity of the film 20 to eliminate detectable distortions of sound produced by changes in such longitudinal velocity and, at the same time, tending to resist or prevent the generation of a longitudinally reflected ripple motion or wave and/or flapping of the 25 film and consequent audible distortions which are produced thereby.

A further object of the invention is to provide a novel inertia-control device utilizing a compressible fluid for maintaining the motion of the 30 film uniform and unaffected by changes in the temperature of the fluid; unaffected by spliced joints in the film; and unaffected by other forces or conditions which tend to cause a change in the velocity of the film.

Other and further objects and advantages of 35 the invention will be apparent from the following description when taken in connection with the accompanying drawings.

Figure 1 shows an illustrative embodiment of 40 the invention as employed in a sound-reproducing apparatus, this view being a fragmentary view in elevation of such an apparatus.

Figure 2 is a fragmentary vertical section taken 45 substantially along the line 2-2 of Figure 3.

Figure 3 is a fragmentary vertical section taken along the line 3-3 of Figure 2.

Figure 4 is a fragmentary horizontal section taken along the line 4-4 of Figure 2.

Figure 5 is a fragmentary view in elevation of 50 a modified form of the invention.

Figure 6 is a fragmentary view in section taken along the line 6-6 of Figure 5.

Figure 7 is a fragmentary vertical section taken 55 along the line 7-7 of Figure 6.

Figure 8 is a view in perspective of an element 60 of the device shown in Figures 5 to 7, inclusive.

Figure 9 is a fragmentary view in elevation of another modified form of the invention; and

Figure 10 is a fragmentary vertical section 65 taken along the line 10-10 of Figure 9.

As shown in Figures 1 to 3 for purposes of illustration, the invention may be embodied in a sound-on-film motion picture reproducer 2 having an electric motor 4 as a common power source 70 for driving the mechanism of the sound picture machine. This mechanism includes an intermittent motion 6 of any suitable or conventional design for intermittently feeding film into and out of the picture projecting beam; a feed sprocket 75 or roller 8 over which the film passes from the intermittent motion 6; a spring-tensioned arm 10 carrying the usual film-engaging roller or rollers for maintaining the film upon the sprocket 8; a drum 12 about which the film passes from 80 the sprocket 8 and from which drum the film

passes over another feed sprocket or roller 14 with which cooperates a spring-tensioned guide 16 and a third feed sprocket or roller 18 with which a spring-tensioned guide 20 cooperates, the film passing from the sprocket 18 between 5 pairs of opposed guide rollers 22 to the film take-up roll or reel 24. The film extends beyond the outer edge of the drum 12 so that the sound track thereon lies outside this edge of the drum and passes across a beam of light projected upon 10 the film by an optical system 26 of suitable conventional design from a light source 28, the beam thereafter passing through the film impinging upon the photo-active electrode of a photoelectric cell 30, connected to the usual amplifier 15 and thereby to the usual sound reproducer.

The motor 4 is connected by the coupling 32 (Fig. 2) to the shaft 34 provided with a worm gear 36, the shaft 34 being mounted in suitable anti-friction bearings 38 supported in opposed walls or partitions of a mechanism housing 40 secured to, or cast integrally with the side wall of the housing, or one portion 42 of the housing, for the sound head of the machine. The worm 36 drives inter-meshing gears 44 and 46, the gear 44 being secured to and driving the shaft 48 of the feed sprocket or roller 14, and the gear 46 being secured to and driving the shaft 50 of the feed sprocket or roller 18. The shaft 50 may also drive through the pulley 52 and belt 54 the 30 take-up roll or reel 24. The shaft 48 also drives through an appropriate mechanism, of which gear 56 secured to the shaft 48 forms a part, the feed sprocket or roller 8 and the intermittent motion 6. The drum 12 is carried upon the shaft 35 58 which is preferably carried in ball bearings 60 and 62, mounted in a wall of the portion 42 of the housing for the sound head and a boss or bracket formed upon or secured to the mechanism housing 40. An inertia member or flywheel 40 64 is pinned or keyed to the outer end of the shaft 58. The inertia member or flywheel 64, as shown in Figs. 1 to 3, comprises a casting having a central apertured disk-like portion or hub 66 and radially-directed, outwardly-extending, 45 angularly-spaced blades 68, or fins of appreciable length. The flywheel is housed within a volute fluid confining housing or casing 70 secured or attached in any convenient manner to the housing for the sound head or to the portion 50 42 thereof. The flywheel-circumscribing wall of the housing or casing 70 may comprise a portion 72 of circular configuration in cross-section merging into a portion 74 of spiral configuration 55 in cross-section, the portion of circular configuration being connected to the portion of spiral configuration by a shelf-like portion 76 against which the compressible fluid, preferably air, within the housing is compressed or driven. An opening in the rear wall 78 of the housing or casing 60 70, which may be provided by an enlargement of the aperture 80 through which the shaft 58 passes, provides fluid or air admission means or port for the housing or casing 70. A fluid or air exhausting means or port may be provided by 65 an opening 82 in the shelf-like portion 76 of the flywheel housing or casing and the rate of flow of the compressible fluid or air through this opening may be regulated by a valve 84 comprising a plate pivoted to the under surface of 70 the shelf-like portion 76 and provided with an operating knob or pin 86, by which the valve may be swung to regulate the size of the opening through which the compressible fluid or air may be exhausted from the flywheel housing or casing. 75

In the operation of the machine, the film passing about a portion of the drum 12 drives this drum, the shaft 58, and the inertia member or flywheel 64. The flywheel, by virtue of its construction in which, as compared with prior flywheels, a considerable amount of material is removed to form the blades or fins 68, is considerably lighter in weight than such prior flywheels. Hence, this novel flywheel reduces the wear upon the film caused by its engagement with the roller 12 frictionally driven by the film. The compression of the confined fluid or air by the blades as they sweep past the shelf 76 in a clockwise direction, the displacing of the fluid or air as the tips of the blades rotate in proximity to the wall portion 72 of circular configuration, and the expansion of the fluid or air above the shelf 76 within the limits of the portion 74 of spiral configuration produce a retarding or dampening effect upon the flywheel and increase the inherent tendency of the fluid, in acting upon the relatively large facial areas of the blades, to oppose a change in speed of the flywheel. These retarding forces are sufficient to dampen the flywheel against changes in speed due to changes in the longitudinal velocity of the film occurring sufficiently rapidly to produce, if undamped, an audible sound distortion but, at the same time, prevent any detectable formation of a wave or ripple motion in the film which would be reflected to the portion of the film on the drum 12 and cause an audible sound distortion.

It appears, from exhaustive tests and observations of machines provided with this flywheel dampened by a compressible fluid, that the longitudinal velocity of the film is maintained sufficiently constant against suddenly occurring changes as to prevent any audible distortion of sound and at the same time eliminates the flapping of the film heretofore caused by the oscillating increase and decrease in the length of the portion of the film or loop between the drum 12 and the feed sprocket or roller 14 and/or the sprocket or roller 8. Also, the compressible fluid exerts a retarding effect which does not vary with the temperature of the fluid.

It will, of course, be apparent that compressible fluids other than air may be employed if desired, although air is preferably employed since it entails no supply cost, does not cause a breakdown of the apparatus if the fluid medium leaks out of its confining casing, and reduces the cost of the confining casing which it is obvious does not need to be rendered proof against leakage of the medium. Where a compressible fluid other than air is employed, the fluid admission and exhaust ports may be eliminated or such ports may be connected by an external or internal conduit or duct.

In the form of the invention shown in Figures 5 to 8, the housing or casing 88 for the flywheel 64 is preferably of cylindrical form and comprises a foraminous cage or wire guard 90 seated within the outwardly bent peripheral flange 92 of a disk 94 secured to the housing for the sound head or to any other suitable fixed portion of the machine. The cage 90 is fastened to the disk 94 as by a plurality of angularly-spaced screws 96, carried by the ring or rim 98 of the cage or guard and threaded into the disk 94. Spacing sleeves 100 may be used in connection with the screws 96 to maintain the face portion of the cage or guard in proper spaced relation to the disk 94. The blades or fins 68 of the flywheel 64 are in this form of the invention provided at their

tips with strips or pieces 102 of felt or similar cushioning material, secured to the blades as by coatings 104 (Fig. 7) of suitable adhesive. Between alternate pairs of blades or fins 68 is mounted a yieldable blade 106 preferably formed of relatively thin sheet metal or other suitable yielding material having opposed wing portions 108 and 110 connected by a flange portion 112 fitting into the space between a pair of blades at the hub thereof and receiving a fastener 114 for securing the yieldable blade 106 to the hub portion 66 of the flywheel. When thus secured, the wing-like portion 108, which is shorter than the wing-like portion 110 of the blade 106, yieldably engages a face of one of the pair of blades 68 of the flywheel, while the wing-like portion 110 of the blade 106 yieldably engages the felt strip 102 carried by the other blade 68 of the pair of adjacent blades of the flywheel. The wing-like portions 110 of all the blades 106 extend well beyond the edges of the flywheel blades 68 but terminate a substantial distance inwardly of the cage or guard 90. During operation, the flywheel of this form of the invention rotates in a clockwise direction as seen in Figure 5. The air, which is driven or displaced by the flywheel as it rotates, exerts a retarding effect upon it sufficiently to maintain the film velocity substantially uniform as against forces tending to effect a sudden change in such velocity and at the same time this dampening effect does not cause flapping of the film. The yieldable or auxiliary blade 106 provide a very convenient means of increasing the facial areas of the flywheel blades without appreciably increasing the weight of the flywheel and, being yieldable, prevent the currents of compressible fluid from causing chattering of the flywheel. Also, it has been found that these yieldable blades, in yielding relative to the blades or fins 68 of the flywheel, tend to act as impelling or retarding wings, further resisting any sudden change in the velocity of the flywheel and preventing the flywheel from becoming part of an oscillating system with the film-driving rollers or sprockets. The housing 88 functions as a guard and is preferably formed of wire as shown, so as not to effect to any appreciable extent the free flow of the compressible fluid or air under the driving force of the flywheel. The felt pieces 102 cushion the blades 106 so that no vibrations will be set up between these blades and the blades 68 of the flywheel proper. In the form of the invention shown in Figures 5 to 8, the flywheel 64, with the auxiliary blades 106, is pinned or keyed to the shaft 58 to rotate therewith at all times.

In the form of the invention shown in Figures 9 and 10, the flywheel 64, provided with the auxiliary blades 106 between alternate pairs of flywheel blades 68, is mounted on an outer end portion 116 of the shaft 58 by roller bearings 118 and 120, having a close fit between the hub 66 of the flywheel and the shaft portion 116 so that the flywheel 64 is frictionally driven by the shaft. A solid flywheel 122 is pinned or keyed to the shaft 58 as by set screw 124 in axially spaced relation to the flywheel 64 and a spacing sleeve 126 is interposed between the flywheel and the rear roller bearing 120, the sleeve having frictional engagement with the flywheel and the bearing, if desired, so as to apply an additional friction tending to cause rotation of the flywheel 64 with flywheel 122 and the shaft 58. Axial movement of the flywheel 64 is prevented by the sleeve 126 and a washer 128 overlapping the bearing 75

ing 118 and secured to the end of the shaft 58 as by a screw 130. The flywheel 122 may, of course, be lighter in weight than the solid flywheels heretofore employed, and it is damped by the 5 frictionally driven and frictionally reactive flywheel 64, which performs its dampening effect in the same manner as the flywheel 64 with the auxiliary blades 106 as previously described with reference to the form of the invention shown in 10 Figures 5 to 8. The flywheel 64, as shown in Figures 9 and 10, in conjoint operation with the flywheel 122, also provides an efficient means for suppressing low frequency irregularities caused by the film-feeding mechanisms and eliminates 15 this inherent deficiency of a system employing a solid undamped flywheel.

It will, therefore, be seen that applicant has provided means tending sufficiently to resist change in longitudinal velocity of the film to 20 eliminate detectable distortions of sound produced by changes in such longitudinal velocity and, at the same time, tending to resist or prevent the generation of a longitudinally reflected 25 ripple motion or wave and/or flapping of the film and consequent audible distortions which are produced thereby; and a novel inertia-control device utilizing a compressible fluid for maintaining the motion of the film uniform and unaffected by changes in the temperature of the fluid; unaffected by spliced joints in the film; and unaffected by other forces or conditions which tend 30 to cause a change in the velocity of the film.

I claim:

1. A phonographic apparatus comprising a 35 frictionally driven record carrier, an inertia member coupled to said carrier and compressible fluid means dampening the inertia member against variations in speed.

2. A phonographic apparatus comprising a 40 frictionally driven record carrier, a flywheel coupled to said carrier and compressible fluid means for dampening the flywheel against variations in speed.

3. Film feeding apparatus comprising a film 45 carrier frictionally driven by the film, an inertia member coupled to said carrier and operatively associated with means providing radial fins operating in an atmosphere of compressible fluid reacting thereupon to dampen the inertia member against changes in velocity.

4. In a film feeding apparatus, a rotary film carrier frictionally driven by the film, a rotary inertia member coupled to the carrier, and means 50 rotating with the inertia member in an atmosphere of compressible fluid for dampening the inertia member against changes in velocity as spliced joints of the film pass the carrier.

5. In a film feeding apparatus, a rotary film carrier frictionally driven by the film, a flywheel 60 coupled to said carrier, a housing for said flywheel filled with a compressible fluid, and means rotating with the flywheel in the atmosphere of compressible fluid in the housing for dampening the flywheel against changes in velocity.

6. In a film feeding apparatus, a rotary film carrier frictionally driven by the film, a flywheel coupled to said carrier, a housing for said flywheel filled with a compressible fluid, and means 65 rotating with the flywheel for propelling the compressible fluid in the housing whereby the reaction of the compressible fluid dampens the flywheel against changes in velocity.

7. In a film feeding apparatus, a rotary film carrier frictionally driven by the film, a flywheel 70 coupled to the carrier, a container providing a

chamber housing the flywheel and air admission and exhaust openings into said chamber, said flywheel having radially extended fins for circulating the air in said chamber from the air admission openings through the air exhaust opening whereby the reaction of the air upon the fins of the flywheel dampens the flywheel against variations in velocity. 5

8. In a film feeding apparatus, a rotary film carrier frictionally driven by the film, a flywheel 10 coupled to the carrier, a container providing a chamber housing the flywheel, air admission and exhaust openings into said chamber, said flywheel having radially extended fins for circulating the air in said chamber from the air admission openings through the air exhaust opening whereby the reaction of the air upon the fins of the flywheel dampens the flywheel against variation in velocity, and means for adjustably regulating the amount of air flowing through 15 one of said chamber openings whereby to adjustably regulate the dampening effect of the air upon the flywheel.

9. In a film feeding apparatus, a rotary film carrier frictionally driven by the film, a flywheel 20 coupled to the carrier, a container providing a volute chamber housing the flywheel and air admission and exhaust openings into said chamber, said flywheel having radially extended fins for circulating the air in said chamber from the air admission openings through the air exhaust opening whereby the reaction of the air upon the fins of the flywheel dampens the flywheel against 25 variations in velocity.

10. In a film feeding apparatus, a rotary film 30 carrier frictionally driven by the film, a flywheel coupled to said carrier and means including a flexible blade rotating with the flywheel in an atmosphere of compressible fluid for dampening the flywheel against variations in velocity. 35

11. In a film feeding apparatus, a rotary film carrier frictionally driven by the film, a flywheel 40 coupled to said carrier, and means including a plurality of flexible and inflexible blades rotating with the flywheel in an atmosphere of compressible fluid for dampening the flywheel against 45 variations in velocity.

12. In a film feeding apparatus, a rotary film carrier frictionally driven by the film, a flywheel 50 coupled to said carrier, said flywheel having a plurality of radially extending inflexible fins, a housing for said flywheel filled with a compressible fluid, and a plurality of flexible blades mounted on said flywheel in yielding relation to said fins and coupling with said fins to dampen the 55 flywheel against variations in velocity.

13. In a film feeding apparatus, a rotary film carrier frictionally driven by the film, a solid flywheel coupled to said carrier, and means frictionally coupled to said solid flywheel and including means rotating in an atmosphere of compressible fluid for frictionally applying dampening forces to the solid flywheel. 60

14. In a film feeding apparatus, a rotary film carrier frictionally driven by the film, a solid flywheel 65 coupled to said carrier and means frictionally coupled to the flywheel and the carrier and rotating in an atmosphere of compressible fluid for frictionally dampening the solid flywheel and the carrier against variations in velocity. 70

15. In a film feeding apparatus, a rotary film carrier frictionally driven by the film, a solid flywheel coupled to the carrier, a second flywheel coupled to the solid flywheel and having radial fins rotating in an atmosphere of compressible 75

fluid for dampening the solid flywheel against variations in velocity.

16. In a film feeding apparatus, a rotary film carrier driven by the film, a solid flywheel coupled to said carrier, a second flywheel coupled to the solid flywheel, a housing for said flywheel filled with a compressible fluid, said second flywheel having radially projecting fins propelling the compressible fluid whereby the reaction of the compressible fluid on the second flywheel serves through the second flywheel to dampen the solid flywheel against variations in velocity.

10 17. In a film feeding apparatus, a rotary film carrier driven by the film, a solid flywheel coupled

to said carrier, a second flywheel coupled to the solid flywheel, a housing for said flywheel filled with a compressible fluid, said second flywheel having radially projecting fins propelling the compressible fluid whereby the reaction of the compressible fluid on the second flywheel serves through the second flywheel to dampen the solid flywheel against variations in velocity, said fins of the second flywheel being inflexible, and a plurality of flexible blades mounted on said second flywheel in yielding relation to said flexible fins.
